UNITED STATES PATENT OFFICE.

RALPH W. BIERER, OF BINGHAMTON, NEW YORK.

BOX FOR THE TOE PORTIONS OF BOOTS OR SHOES.

1,373,855.

Specification of Letters Patent.

Patented Apr. 5, 1921.

Application filed July 12, 1919. Serial No. 310,355.

To all whom it may concern:

Be it known that I, RALPH W. BIERER, a citizen of the United States, residing in Binghamton, in the county of Broome and 5 State of New York, have invented an Improvement in Boxes for the Toe Portions of Boots or Shoes, of which the following description, in connection with the accompanying drawings, is a specification, like characters on the drawings representing like parts.

This invention relates to a novel construction of box for the toe portion of a boot or shoe, whereby a superior shoe may be produced at a minimum cost.

To this end, the box is composed of a member of celluloid, pyroxylin or like modification of cellulose, which will be hereinafter referred to as the celluloid member, a member or layer of paper which is capable of being stretched without splitting or tearing, preferably a paper found on the market and known as crape paper, said paper layer being adhesively affixed to the upper surface 20 of the celluloid member, and a layer or member of cloth which is adhesively affixed to the lower surface of said celluloid member. The celluloid member is normally flat and of suitable shape to enable it to conform to 25 the shape of the toe portion of the shoe in which it is to be incorporated.

The paper and cloth members are shaped like the celluloid member but are slightly larger, and are formed by a suitable cutting 35 die. In practice a plurality or bunch of the paper members are simultaneously cut from a plurality of sheets or layers of paper, and in like manner the cloth members are cut from a plurality of sheets or layers of cloth.

40 The bunch or plurality of paper members, usually about 18 in number, is dipped in a solvent for the celluloid, preferably a solution of acetone and alcohol, and then passed through an ordinary clothes wringer, which 45 has its rolls adjusted so as to express the surplus solvent and leave in the paper the proper or desired amount of the solvent. The bunch of cloth members is treated in the same manner, and it has been found that 50 a bunch of about 36 layers of cloth can be handled satisfactorily. Immediately after the cloth and paper members have been passed through the wringer, they are assembled in a vertical pile with a celluloid 55 member between adjacent cloth and paper

members. This operation is performed with the aid of a vertical guide, which is curved to conform with the curve of the rear edges of the cloth and paper members.

The mode of procedure is as follows: A 60 cloth member is placed against the guide, then a celluloid member is placed on top of the cloth with its rear edge removed from the guide a distance equal to the overlap desired on the cloth. Two paper members are 65 then placed over the celluloid member with their rear edges against the vertical guide. A celluloid member is then placed upon the paper with the rear edge a distance from the vertical guide equal to the overlap desired 70 on the cloth members. Two members of cloth are then placed on top of the celluloid member with their rear edges touching the vertical guide and then another celluloid member is placed on top of the cloth at a 75 distance from the vertical guide equal to the overlap desired on the cloth and then two paper members are applied, and so on until the desired number of members have been assembled to form the number of toe boxes 80 desired, which number is usually 36, but any other number of boxes may be assembled according to the number of shoes in the case being made up. As soon as the correct number of boxes have been assembled, they are 85 placed in a practically air tight can, where in the solvent in the paper and cloth members acts on the celluloid members and said paper and cloth members become adhesively affixed to the celluloid members. It usually 90 requires about 30 minutes for the celluloid to become somewhat mulled and sufficiently pliable to last, but it is preferred to leave the boxes in the cans for a longer period and preferably for about two hours, at the end 95 of which time the celluloid members are in good condition to be lasted.

The three members comprising a box blank are then removed from the can as a unit, and placed in position in the boot or 100 shoe upper, and the upper and celluloid member are then stretched by a suitable pull or pressure, compressed, bent or curved so as to conform to the shape of the last and form the box for the toe portion of the shoe. 105

While the box is being shaped, the crape layer remains unbroken as it is of such nature or construction as to enable it to be expanded or stretched without splitting or tearing.

The crape paper layer is materially thinner than the cloth layer, which is of material advantage in the manufacture of the box, as the paper takes up materially less solvent than the cloth layer, thereby effecting a very material saving in the quantity of solvent used by the shoe manufacturer during a given period of time, as for instance a year, and the paper is much cheaper than the cloth. The paper layer is very thin and enables the cloth layer below it to be clearly seen, and this is of advantage when the blanks are piled up, as the cloth and paper blanks can be piled up with their rear edges flush, thereby obtaining a more uniform overlap of cloth over the rear edge of the celluloid member.

The crape paper layer also reduces the thickness of the box, thereby increasing the pliability of the latter and rendering it more resilient or springy, so that when incorporated in the shoe, if it should become slightly dented in by a light blow, it will automatically spring back into shape, and in case it is dented in by a heavy blow, it can be forced or sprung back into shape by hand.

So also the thinner box permits the upper of the shoe to be lasted closer to the last and thereby better conform to the shape of the same, with the result that a neater and more finished shoe can be produced, especially those having narrow pointed toes, and also the operation of lasting the upper is made easier.

The thinner box enables the shoe to be provided with a smoother upper as it avoids a break in the upper where the box ends. So also any tendency of the box to curl downward at its rear edge is avoided with the result that the inside of the shoe at the toe portion is smooth and thus avoids hurting the foot of the wearer.

Furthermore the thin paper enables the rear edge of the cloth member to be clearly seen, which enables the celluloid member to be better positioned in the shoe as the rear edge of the cloth is thus available as a guide.

The particular features of the invention will be pointed out in the claims at the end of this specification.

Figure 1 represents a shoe embodying this invention.

Fig. 2, a longitudinal section on an enlarged scale of the toe portion of the shoe shown in Fig. 1.

Fig. 3, a cross section on an enlarged scale of the toe portion of the shoe shown in Fig. 1, and

Fig. 4, a plan view of the box blank in its flat condition.

Referring to Fig. 4, 10 represents the celluloid blank; 12 the cloth layer affixed to the under surface of the celluloid blank, and 13 the crape paper layer affixed to the upper surface of the celluloid blank.

It will be observed that the cloth and paper layers 12, 13, project beyond or overlap the rear edge 14 of the celluloid blank.

The formation of the crape paper which enables the latter to be expanded or stretched when the box blank is pressed into shape on the last, not shown, while being incorporated in the shoe 15, is represented by the wavy lines 16.

In Figs. 2 and 3, the box is shown as incorporated in a shoe provided with the cloth lining 17, and the vamp lining 19 interposed between the box toe and the vamp 20 and while a space is represented in Fig. 2 between the cloth lining 17 and the vamp lining 19, in order to illustrate clearly the box within the shoe, such space does not exist in the finished shoe represented in Fig. 1, by reference to which it will be seen that the upper does not break where the box ends, but presents a smooth and unbroken surface.

One construction of shoe embodying the improved box is herein shown, but it is not desired to limit the invention in this respect as the box is capable of being used with all makes of shoes having toe boxes.

The finished shoe represented in Fig. 1 possesses the advantages above referred to.

I claim.

1. A box for the toe portions of shoes, comprising a celluloid member, a cloth member adhesively affixed to the under surface 100 of said celluloid member, and a member of crape paper adhesively affixed to the upper surface of said celluloid member.

2. A box for the toe portions of shoes comprising a celluloid member, a member 105 of fibrous material adhesively affixed to one surface of said celluloid member, and a member of paper capable of being expanded or stretched without tearing or splitting, adhesively affixed to the opposite surface of 110 said celluloid member.

3. A box for the toe portions of shoes having a celluloid member and a member of paper capable of being expanded or stretched without tearing or splitting adhesively affixed to said celluloid member.

In testimony whereof, I have signed my name to this specification.

RALPH W. BIERER.
